STRAP BUCKLE

Filed Oct. 11, 1928

74 Inventor
Arthur F. Bernard,
By Thomas A. Jenkins,
Attorney

UNITED STATES PATENT OFFICE

ARTHUR F. BERNARD, OF PROVIDENCE, RHODE ISLAND

STRAP BUCKLE

Application filed October 11, 1928. Serial No. 311,852.

My invention relates to strap buckles and specifically includes improvements in strap tighteners adapted to be inserted in a strap for expanding and contracting the length of 5 the strap of the type shown in the patent to John D'Alo, 1,692,079, issued Nov. 28, 1928 for Automatic strap tightener.

The automatic strap tightener feature of my invention is especially adapted for use 10 in connection with a limb encircling strap, particularly a wrist watch bracelet and is adapted to form a flexible strap tightener of the type shown therein and in addition an 15 expansible strap tightener of a type capable of opening up to permit removal of the strap from the wrist and adapted when in closed position to flexibly and firmly clasp the strap to the wrist so that the strap will be bound to the wrist without inconvenience 20 during all movements of the arm and wrist.

One particular feature of my invention resides in the fact that I am enabled to attach a strap end to the front connector section so that when attached to the wrist the top of 25 said front connector section may be visible and suitably ornamented if desired in any desired fashion. To this end I provide means to attach a strap end to said front connector section longitudinally slidable to 30 the inner end thereof to expose the top of the front connector section to view when said tightener is attached in use and longitudinally slidable to the outer end thereof to permit expansion of the flexible strap tightener when the front connector section is pivoted to open position away from the back connector section. In order to permit an expansion of the automatic strap tightener substantially equal to that provided in the co- 35 pending application referred to, I prefer- 40 ably pivotally mount the intermediate guide rail connector section on the outer end of the back connector section and attach the other strap end to the inner end thereof and 45 omit any means to permanently lock the inner end of the intermediate guide rail connector section to the back connector section, whereby when the front connector section is 50 pivoted away from the back connector section, the intermediate connector section may

be pivoted outwardly to correspondingly increase the length of the strap. In order to permit the outward pivot of the intermediate guide rail connector section and attached strap end on the back connector section, I preferably provide a construction wherein the strap end is attached to the intermediate connector section over it when in closed position in place of under it as shown in the aforesaid D'Alo patent. 55

When the invention is employed with a wrist watch or other article having bar means for attachment of the strap thereto as I employ in combination with an automatic strap tightener of the type shown herein to expand the strap for removal purposes, said strap ends may be permanently attached to said bar means. A further feature of my invention relates therefore to an improved buckle means to permanently attach the strap 60 end to said bar means. 65

A further object of my invention relates to the provision of buckle means for use with straps of a construction simple and easy to make and of ornamental appearance. 70

These and such other objects of my invention as may hereinafter appear will be best understood from a description of one embodiment thereof, such as is shown in the accompanying drawings. 75

In the drawings, Fig. 1 is a perspective view of a wrist watch bracelet employing my invention with the automatic strap tightener in closed position, exposing the top wall of the front connector section, the 80 position my invention normally takes when used on a wrist. 85

Fig. 2 is a longitudinal sectional view taken through the center of the automatic strap tightener. 90

Fig. 3 is a transverse sectional view taken along the line 3-3 of Fig. 2 looking inwards from the outer end of the automatic strap tightener. 95

Fig. 4 is a side elevation of the automatic strap tightener showing both the front and intermediate connector sections in half open position.

Fig. 5 is a perspective view similar to Fig. 1 with the front and intermediate connector 100

sections of my improved strap tightener pivoted to an open position to permit the wrist watch strap to be slipped off the wrist.

Fig. 6 is a longitudinal sectional view taken through the buckle means I preferably employ to permanently attach the strap end to the wrist watch bar.

Fig. 7 is a disassembled rear perspective view of the buckle means and bar means shown in Fig. 6.

In the drawings, wherein like characters of reference indicate like parts throughout, 10 generally indicates an inelastic strap adapted to encircle the wrist. Said strap may be constructed of leather, woven wire, or any suitable material. 12 generally indicates a wrist watch interposed in the circumference of said strap, said wrist watch being provided with the transversely extending bar means 13 projecting from each end thereof for attachment of each strap end thereto. Though I have shown my invention in use with a strap having a wrist watch attached, it is obvious that any other type of ornament may be used instead, or that the strap may surround the wrist without the interposition of any ornament therein.

16 generally indicates my improved strap tightener. In the preferred embodiment 30 shown my improved strap tightener includes a back connector section 14, preferably provided with the forwardly protruding side flanges 18 in the embodiment shown comprising lugs only protruding at each end thereof. 35 In the description and claims I refer to the center of the strap tightener as that portion of the strap tightener on which the front connector section is pivoted on the back connector section and I employ the words "inner" 40 and "outer" in relation thereto. I also provide the front connector section 20 and I provide means to pivotally mount the inner end of the front connector section 20 on the inner end of the back connector section 14. 45 In my preferred embodiment said means comprises the pivot pin 26 suitably mounted in suitable pivot holes in the inner ends of the flanges 18 of the back connector section 14 and the inner ends of the downwardly projecting side flanges 32 of the front connector section 20. The outer ends of said side flanges 32 are suitably provided with the depressions 50 or holes 30 which cooperate with means later to be described to form means to clamp or lock said front and back connector sections together.

Said front connector section 20 is provided with means to attach a strap end thereto. For certain features of my invention said strap end 60 may be attached to any desired portion of the front connector section 20. In order, however, to have the strap end attached to the inner end of the front connector section when in closed position and to move to the outer end to increase the length of the strap 10 for

removal purposes when said front connector section 20 is pivoted to open position, I preferably provide the side flanges 32 of said front connector section with the longitudinal slots 33 therein extending longitudinally thereof near the top wall 31 thereof and I provide the bar 22 slidably loosely mounted within said slots provided with suitable means to attach an end 24 of the strap thereto. In my preferred embodiment said means 23 75 comprises the bail 23 having the ends 25 thereof pivotally attached to the ends of the bar 22 exterior of said front connector side flanges 32 and slideable with said bar 22 over said front connector section so as to permit the bar 22 to slide within said front connector section and said bail 23 to slide correspondingly on the outside of said front connector section over the top thereof. The strap end 24 is suitably attached to the inner end of the bail in any suitable manner.

While any means may be provided on said back connector section protruding laterally therefrom to cooperate with the depressions 30 to lock said front connector section 20 to said back connector section 14, I preferably construct said means as follows as a part of the intermediate guide rail connector section 34 now to be described. In my preferred embodiment said guide rails 34 comprise the U-shaped member 37 having the outer ends 35 of the guide rail legs 34 thereof terminating in the lugs 28 adapted to extend through the pivot holes 19 in the outer ends of the forwardly protruding side flanges 18 of the back connector section 14. I pivotally mount said U-shaped guide rail member 37 on the outer end of the back connector section 14 and additionally form the lateral projections or lugs 28 projecting therefrom through said pivot holes 19 adapted to register in the depressions 30 in the outer ends of the front connector section side flanges 32 to lock said front and back connector sections in closed position.

I provide the plate member 38 having the holes 39 therein to receive and bind the legs 34 of said U-shaped member 37 together near the outer ends 35 thereof. The springs 40 are mounted on said guide rail legs 34 and have their outer ends 42 abut the inner side of the plate member 38. I provide the sliding member 44 provided with the outer bail ends 47. The clamping member 49 for attachment of the strap end 48 thereto over said intermediate connector section 37 when said intermediate connector section is pivoted to closed position between said front and back connector sections is provided with the pivot lugs 46 projecting from the outer ends thereof for pivotal mounting thereof in suitable holes on said bail 47. Said sliding member 44 is provided with the holes 50 to receive the guide rails 34 therein underneath said strap end 48. The inner ends 52 of said springs are adapted to abut the outer face 54 of the slid-

ing member and it is thus obvious that the springs 40 will at all times tend to force the sliding member 44 with the attached strap end 48 inwards to at all times tighten the strap 10. If in use the wrist is moved causing the strap to expand, it is obvious that the springs 40 will continuously contract at all times to tightly bind the strap to the wrist, the strap end 48 sliding on the intermediate connector section 37 on the guide rails 34 thereof between said front and back connector sections. When the device is in closed position as shown in Fig. 1, it is obvious that the wrist watch or other object will be continuously bound to the 15 wrist. When the front connector section 20 is swung to open position as shown in Fig. 5 to open up said sections the strap may be readily removed from the wrist. As is illustrated in Figs. 4 and 5 as the intermediate connector section 37 pivots outward it moves the end 48 of the strap 10 outwards to increase the length of the strap and as the front connector section 20 pivots to open position the strap end 24 may readily slide from the inner to the outer end thereof in said slots 33 thereby readily also increasing the length of said strap for removal purposes. It is apparent, however, that when the front connector section 20 is pivoted to closed position the 20 strap end 24 will slide to the inner end thereof to permit the ornamented top 31 thereof to be exposed to view on the wearer's wrist. It is also apparent that when the intermediate connector section 37 is pivoted to closed position it will be permanently retained in said position between said front and back connector sections so as to permit ready longitudinal slidable movement of the member 44 with attached strap end 48 on said guide rails 34 25 against the tension of said springs 40.

As stated hitherto, I provide in combination, a split limb encircling strap having the split ends 24 and 48 and an article such as the wrist watch 12 having the bar means 13 on each end thereof for attachment thereof to said strap, an expansible strap tightener interposed in said strap, and means to fixedly attach each end 24 and 48 respectively of said strap to said bar means. In my preferred embodiment the improved type of attaching means to fixedly attach each end of said strap to the bar means 13 comprises the plate member 60 having the bar receiving downwardly projecting hook 62 at the outer end thereof preferably provided with the central cut out portion 64. Said member 60 has a strap clamp 66 pivoted to the rearwardly projecting side flanges 68 thereof at the inner end thereof, said clamp having a preferably 50 toothed edge 70 adapted to clamp the strap end 24 against said member 60 and an outwardly projecting tongue 72 rearwardly curved as at 74 and preferably having a finger nail operative portion 76 projecting outwardly therefrom adapted to pivot rearwards

through said cut away portion in the end hook 62 and adapted to be permanently retained in locked position under said bar means 13.

It is understood that my invention is not limited to the specific embodiment shown and that various embodiments may be shown without departing from the spirit and scope of the appended claims.

What I claim is:

1. A strap tightener, adapted to be inserted in a strap for expanding and contracting the length of the strap, comprising, a back connector section having forwardly protruding side flanges having pivot holes therein near their outer ends, a front connector section having a top wall and side flanges projecting rearwardly therefrom having longitudinal slots therein near the top wall thereof and depressions therein near the outer ends thereof, means to pivotally mount the inner end of the front connector section on the inner end of the back connector section, a bar longitudinally slidable within said longitudinal slots, a bail having the ends thereof pivotally attached to the ends of said bar and slidable with said bar over said front connector section adapted to have a strap end attached thereto, longitudinal guide rails comprising a U-shaped member having the outer end of the guide rail legs thereof flaring outwardly and terminating in lugs adapted to extend through said pivot holes on the outer end of the back connector section side flanges for pivotally mounting said member thereon having ends projecting through said pivot holes adapted to register in the depressions in the outer ends of the front connector section side flanges to lock said sections together, a plate member having holes therein to receive and bind the legs of said U-shaped member together near the outer pivot ends thereof, springs mounted on said guide rail legs having their outer ends abutting said plate and a sliding member riding on said guide rails having the outer end thereof abutting the inner ends of said springs and having means therein for pivotal attachment of the other strap end thereto over said guide rails, whereby said guide rail member and attached strap end may be pivoted to closed position between said locked front and back connector sections and the length of the strap may be increased when said guide rail member is pivoted to open position and whereby the bail bar and attached strap end may slide to the inner ends of said side flange slots to display the top wall of the front connector section when said front connector section is pivoted on said back connector section to closed position and may slide to the outer ends of said side flange slots to increase the length of the strap when said front connector section is pivoted on said back connector section to open position.

2. A strap tightener adapted to be inserted

in a strap for expanding and contracting the length of the strap, comprising a back connector section, a front connector section having a top wall and side flanges projecting rearwardly therefrom having longitudinal slots therein near the top wall thereof, means to pivotally mount the inner end of the front connector section on the inner end of the back connector section, a bar longitudinally slideable within said longitudinal slots, a bail having the ends thereof pivotally attached to the ends of said bar and slideable with said bar over said front connector section adapted to have a strap end attached thereto, and means to clamp said front and back connector sections together in closed position, whereby the bail bar and attached strap end may slide to the inner ends of said side flange slots to display the top wall of the front connector section when said front connector section is pivoted on said back connector section to open position.

3. A strap tightener adapted to be inserted in a strap for expanding and contracting the length of the strap, comprising, a back connector section, a front connector section having a top wall and side flanges projecting rearwardly therefrom having longitudinal slots therein near the top wall thereof, means to pivotally mount the inner end of the front connector section on the inner end of the back connector section, a bar longitudinally slideable within said longitudinal slots, a bail having the ends thereof pivotally attached to the ends of said bar and slideable with said bar over said front connector section adapted to have a strap end attached thereto, and an intermediate connector section having means for attachment of a strap end thereto pivotally mounted on the outer end of said back connector section and means to clamp said front and back connector sections together enclosing said intermediate connector section, whereby said intermediate connector section and attached strap end may be pivoted to closed position between said locked front and back connector sections and the length of the strap may be increased when said intermediate connector section is pivoted to open position and whereby the bail bar and attached strap end may slide to the inner ends of said side flange slots to display the top wall of the front connector section when said front connector section is pivoted on said back connector section to closed position and may slide to the outer ends of said side flange slots to increase the length of the strap when said front connector section is pivoted on said back connector section to open position.

4. A strap tightener adapted to be inserted in a strap for expanding and contracting the

length of the strap, comprising a back connector section having forwardly protruding side flanges, having pivot holes therein near their outer ends, a front connector section having a top wall and side flanges projecting rearwardly therefrom near the top wall thereof having longitudinal slots therein near the top wall thereof and depressions therein near the outer ends thereof, means to pivotally mount the inner end of the front connector section on the inner end of the back connector section, a bar longitudinally slideable within said longitudinal slots, a bail having the ends thereof pivotally attached to the ends of said bar and slideable with said bar over said front connector section adapted to have a strap end attached thereto an intermediate connector section having lugs projecting from the outer end thereof adapted to extend through said pivot holes on the outer end of the back connector section side flanges for pivotally mounting said member thereon adapted to register in the depressions in the outer ends of the front connector section side flanges to clamp said sections together and having means for pivotal attachment of the other strap end thereto over said intermediate connector section when said intermediate connector section is pivoted to closed position between said front and back connector sections, whereby said intermediate connector section and attached strap end may be pivoted to closed position between said locked front and back connector sections and the length of the strap may be increased when said intermediate connector section is pivoted to open position and whereby the bail bar and attached strap end may slide to the inner ends of said side flange slots to display the top wall of the front connector section when said front connector section is pivoted on said back connector section to closed position and may slide to the outer ends of said side flange slots to increase the length of the strap when said front connector section is pivoted on said back connector section to open position.

5. A strap tightener, adapted to be inserted in a strap for expanding and contracting the length of the strap, comprising a back connector section having forwardly protruding side flanges having pivot holes therein near their outer ends, a front connector section having a top wall and side flanges projecting rearwardly therefrom having means to attach a strap end thereto and depressions therein near the outer ends thereof, means to pivotally mount the inner end of the front connector section on the inner end of the back connector section, an intermediate connector section having lugs projecting from the outer end thereof adapted to extend through said pivot holes on the outer end of the back connector section side flanges for pivotally mounting said intermediate connector section thereon adapted to register in the de-

- pressions in the outer ends of the front connector section side flanges to clamp said section together and having means for pivotal attachment of the other strap end thereto over said intermediate connector section when said intermediate connector section is pivoted to closed position between said front and back connector sections, whereby said intermediate connector section and attached strap end may be pivoted to closed position between said locked front and back connector sections and the length of the strap may be increased when said intermediate connector section is pivoted to open position. 5 70
- 10 6. A strap tightener, adapted to be inserted in a strap for expanding and contracting the length of the strap, comprising, a back connector section, a front connector section having means to attach a strap end thereto longitudinally slidable thereon, means to pivotally attach the inner end of said back connector section to the inner end of the front connector section, means to clamp the outer end of the front connector section to the outer end of said back connector section when superimposed thereon, an intermediate connector section pivotally mounted on the outer end of said back connector section having guide rails extending longitudinally of said back connector section, springs mounted on said guide rails having the outer ends thereof abutting a portion of the intermediate connector section near the outer end thereof and a sliding member riding on said guide rails having the outer end thereof abutting the inner ends of said springs and having means thereon for pivotal attachment of the other strap end thereto over said guide rails, whereby said intermediate connector section and attached strap end may be pivoted to closed position between said front and back connector sections and the length of the strap may be increased when said intermediate connector section is pivoted to open position. 15 75
- 20 7. A strap tightener adapted to be inserted in a strap for expanding and contracting the length of the strap, comprising, a back connector section, a front connector section having means to attach a strap end thereto longitudinally slidable thereon, means to pivotally attach the inner end of said back connector section to the inner end of the front connector section, an intermediate connector section pivotally mounted on the outer end of said back connector section and a member longitudinally resiliently slidably mounted on said intermediate connector section having means thereon for attachment of the other strap end over said intermediate connector section when said intermediate connector section is pivoted to closed position between said connector sections and means to clamp the outer end of the front connector section to the outer end of the back connector section when superimposed thereon enclosing said intermediate connector section, whereby said intermediate connector section and attached strap end may be pivoted to closed position between said locked front and back connector sections and the length of the strap may be increased when said intermediate connector section is pivoted to open position and whereby the attached strap end may slide to the inner end of said front connector section to display the top wall of the front connector section when said front connector section is pivoted on said back connector section to closed position and may slide to the outer end of said front connector section to increase the length of the strap when said front connector section is pivoted on said back connector section to open position. 25 90
- 30 8. A strap tightener adapted to be inserted in a strap for expanding and contracting the length of the strap, comprising, a back connector section, a front connector section having means to attach a strap end thereto longitudinally slidable thereon, means to pivotally attach the inner end of said back connector section to the inner end of the front connector section, an intermediate connector section pivotally mounted on the outer end of said back connector section and a member longitudinally resiliently slidably mounted on said intermediate connector section having means thereon for attachment of the other strap end over said intermediate connector section when said intermediate connector section is pivoted to closed position between said connector sections and means to clamp the outer end of the front connector section to the outer end of the back connector section when superimposed thereon enclosing said intermediate connector section, whereby said intermediate connector section and attached strap end may be pivoted to closed position between said locked front and back connector sections and the length of the strap may be increased when said intermediate connector section is pivoted to open position and whereby the attached strap end may slide to the inner end of said front connector section to display the top wall of the front connector section when said front connector section is pivoted on said back connector section to closed position and may slide to the outer end of said front connector section to increase the length of the strap when said front connector section is pivoted on said back connector section to open position. 35 95
- 40 9. A strap tightener adapted to be inserted in a strap for expanding and contracting the length of the strap, comprising, a back connector section, a front connector section having means to attach a strap end thereto, means to pivotally attach the inner end of said back connector section to the inner end of the front connector section, means to clamp the outer end of the front connector section to the outer end of said back connector section when superimposed thereon, an intermediate connector section pivotally mounted on the outer end of said back connector section and a member longitudinally resiliently slidably mounted on said intermediate connector section having means thereon for attachment of the other strap end over said intermediate connector section when said intermediate connector section is pivoted to closed position between said connector sections and means to clamp the outer end of the front connector section to the outer end of the back connector section when superimposed thereon enclosing said intermediate connector section, whereby said intermediate connector section and attached strap end may be pivoted to closed position between said locked front and back connector sections and the length of the strap may be increased when said intermediate connector section is pivoted to open position and whereby the attached strap end may slide to the inner end of said front connector section to display the top wall of the front connector section when said front connector section is pivoted on said back connector section to closed position and may slide to the outer end of said front connector section to increase the length of the strap when said front connector section is pivoted on said back connector section to open position. 45 105

section pivotally mounted on the outer end of said back connector section, a member longitudinally resiliently slidably mounted on said intermediate connector section having means thereon for attachment of the other strap end over said intermediate connector section when said intermediate connector section is pivoted to closed position between said connector sections and means to clamp the outer end of the front connector section to the outer end of the back connector section when superimposed thereon enclosing said intermediate connector section, whereby said intermediate connector section and attached strap end may be pivoted to closed position between said locked front and back connector sections and the length of the strap may be increased when said intermediate connector section is pivoted to open position.

10. A strap tightener adapted to be inserted in a strap for expanding and contracting the length of the strap, comprising, a back connector section, a front connector section having means to attach a strap end thereto, longitudinally slidable thereon, means to pivotally attach the inner end of said back connector section to the inner end of the front connector section, an intermediate connector section pivotally mounted on the outer end of said back connector section having means thereon for attachment of the other strap end over said intermediate connector section when said intermediate connector section is pivoted to closed position between said connector sections and means to clamp the outer end of the front connector section to the outer end of the back connector section when superimposed thereon enclosing said intermediate connector section, whereby said intermediate connector section and attached strap end may be pivoted to closed position between said locked front and back connector sections and the length of the strap may be increased when said intermediate connector section is pivoted to open position.

20. A strap tightener adapted to be inserted in a strap for expanding and contracting the length of the strap, comprising, a back connector section, a front connector section having means to attach a strap end thereto, longitudinally slidable thereon, means to pivotally attach the inner end of said back connector section to the inner end of the front connector section, an intermediate connector section pivotally mounted on the outer end of said back connector section having means thereon for attachment of the other strap end over said intermediate connector section when said intermediate connector section is pivoted to closed position between said connector sections and means to clamp the outer end of the front connector section to the outer end of the back connector section when superimposed thereon enclosing said intermediate connector section, whereby said intermediate connector section and attached strap end may be pivoted to closed position between said locked front and back connector sections and the length of the strap may be increased when said intermediate connector section is pivoted to open position.

30. A strap tightener adapted to be inserted in a strap for expanding and contracting the length of the strap, comprising, a back connector section, a front connector section having means to attach a strap end thereto, longitudinally slidable thereon, means to pivotally attach the inner end of said back connector section to the inner end of the front connector section, an intermediate connector section pivotally mounted on the outer end of said back connector section having means thereon for attachment of the other strap end over said intermediate connector section when said intermediate connector section is pivoted to closed position between said connector sections and means to clamp the outer end of the front connector section to the outer end of the back connector section when superimposed thereon enclosing said intermediate connector section, whereby said intermediate connector section and attached strap end may be pivoted to closed position between said locked front and back connector sections and the length of the strap may be increased when said intermediate connector section is pivoted to open position.

40. A strap tightener, adapted to be inserted in a strap for expanding and contracting the length of the strap, comprising, a back connector section, a front connector section having means to attach a strap end thereto longitudinally slidable thereon, means to pivotally attach the inner end of said back connector section to the inner end of the front connector section, means to clamp the outer end of the front connector section to the outer end of said back connector section when superimposed thereon, and means to attach the other strap end to the back connector section, whereby the attached strap end may slide to the inner end of said front connector section to display the top wall of the front connector section when said front connector section is pivoted on said back connector section to closed position and may slide to the outer end of said front connector section to

increase the length of the strap when said front connector section is pivoted on said back connector section to open position.

12. A strap tightener, adapted to be inserted in a strap for expanding and contracting the length of the strap, comprising, a back connector section, a front connector section having means to attach a strap end thereto longitudinally slidable thereon, means to pivotally attach the inner end of said back connector section to the inner end of the front connector section, means to clamp the outer end of the front connector section to the outer end of said back connector section when superimposed thereon and means to resiliently attach the other strap end to the back connector section, whereby the attached strap end may slide to the inner end of said front connector section to display the top wall of the front connector section when said front connector section is pivoted on said back connector section to closed position and may slide to the outer end of said front connector section to increase the length of the strap when said front connector section is pivoted on said back connector section to open position.

In testimony whereof I affix my signature.
ARTHUR F. BERNARD.
